UNITED STATES PATENT OFFICE.

JULIAN DORIOT, OF BLUFFTON, OHIO.

NON-REFILLABLE BOTTLE.

SPECIFICATION forming part of Letters Patent No. 761,364, dated May 31, 1904.

Application filed January 11, 1904. Serial No. 188,618. (No model.)

To all whom it may concern:

Be it known that I, JULIAN DORIOT, a citizen of the United States, residing at Bluffton, in the county of Allen and State of Ohio, have 5 invented a new and useful Non-Refillable Bottle, of which the following is a specification.

My invention relates to non-refillable bottles such as are employed for preventing the fraudulent substitution of an inferior grade 10 of material for that originally contained by the bottle, and has for its object to produce a comparatively simple inexpensive device of this character which will be efficient in operation and one in which the valve may be 15 locked against movement during transportation.

To these ends the invention comprises the novel features of construction and combination of parts more fully hereinafter described.

20 In the accompanying drawings, Figure 1 is a vertical longitudinal section through a bottle-neck, showing my device applied thereto. Fig. 2 is a similar view showing the device in discharging position. Fig. 3 is a view of the 25 parts of the valve in perspective.

Referring to the drawings, it will be seen that I have illustrated my improved device as applied to a bottle 1 of the usual construction having a neck 2 terminating in a discharge- 30 mouth 3, these parts being composed of glass or other suitable material.

In the device constituting the subject-matter of this invention, 4 designates an outer primary tubular sleeve or casing seated in the 35 neck of the bottle and secured therein by a retaining cap or member 5, which engages over the outer end of the casing and is cemented or otherwise permanently secured to the bottle-neck to prevent removal of the casing. Disposed concentrically within the casing 4 is a secondary tubular sleeve or casing 6 of smaller diameter than the primary casing, thereby producing an intervening discharge-passage 7, with which discharge-openings 8, provided through the wall of the casing 6, communicate, as do also safety-openings 8', formed through the casing 6 adjacent to its upper end for the purpose which will hereinafter appear. The casing 6, the upper 50 end of which is closed by a wall 9, is provided

at its lower end with a peripheral flange 10, designed to seat above an internal flange 11 on the lower end of casing 4 and is secured in place by a coupling sleeve or member 12, having adjacent to its upper end a peripheral 55 exterior flange 13 bearing beneath the flange 11. The member 12, which is of tubular form, is exteriorly threaded above the flange 13 for engagement with the lower end of casing 6 and is of sufficient length to receive a 60 cork packing 14, which fits the neck of the bottle to prevent liquid creeping between the same same and the casing 4. From this arrangement it is apparent that the member 12, the upper end of which projects sufficiently 65 above the flange 10 to form a valve-seat 15, securely couples the lower ends of the casings 4 and 6 for securing the latter within the former.

Disposed loosely within the lower end of 70 casing 6 for movement longitudinally of the latter is a valve 16, which is normally pressed to its seat by an overlying expanded spring 17, having bearing at its ends upon the upper end of the valve and beneath the wall 9, thereby preventing passage of liquid into the bottle through its neck when the valve is in operative position. It may here be said that the weight of the valve is such that when the bottle is turned to discharging position the 75 resistance of the spring will be overcome and permit the valve to slide forward, whereby the liquid may pass outward through openings 8 and passage 7 in the usual manner, but that the spring will hold the valve to its seat except when the bottle is turned downward past a horizontal position. Thus it is apparent 80 that refilling of the bottle is wholly precluded.

Tapped through an internally-threaded opening 18 in the outer end wall 9 of casing 90 6 is a key 19, provided at its outer end with a suitable finger-piece by which the key may be operated. This key, which bears at its inner end upon the outer end of the valve, serves to lock the latter against movement during 95 transportation. When, however, the bottle is to be used, the key is entirely removed, thereby permitting free movement of the valve for discharging the liquor, as above described. If after the bottle has been emptied an at- 100

tempt be made to refill the same by the employment of a pressure-pump, the pressure acting through opening 18 on the valve will force the latter to its seat, and if under these 5 conditions the opening 18 be plugged then the pressure will act upon the valve for a like purpose through the safety-openings 8'.

From the foregoing it will be seen that I produce a simple inexpensive device which 10 may be practically applied to bottles of the ordinary form now in general use and will serve in practice to prevent refilling of the latter, it being understood, of course, that after filling the bottle initially the mechanism here- 15 in described is seated and secured in place in the neck. In attaining these ends I do not limit myself to the precise details herein set forth, inasmuch as minor changes may be made without departing from the spirit of 20 the invention.

Having thus described my invention, what I claim is—

1. The combination with a bottle and its neck, of a primary tubular casing seated in 25 the latter, a member attached to the bottle and engaging the casing to retain the same in position, a secondary tubular casing disposed within the primary casing, a coupling member for connecting said casings, a valve mov- 30 ably disposed within the secondary casing, a seat for said valve, and a spring for moving the valve to seating position.

2. The combination with a bottle and its neck, of a primary tubular casing seated in the latter, a secondary tubular casing disposed 35 in the primary casing and having discharge-openings, the secondary casing being of smaller diameter than the primary casing to produce a discharge-passage with which the openings communicate, a coupling member 40 for connecting the casings, a valve movably disposed within the secondary casing, a seat for said valve, and a spring for pressing the valve normally to its seat.

3. The combination with a bottle and its 45 neck, of a primary tubular casing seated in the latter and provided with a flange, a secondary tubular casing disposed within the primary casing and having a flange to seat above the first-named flange, a tubular coup- 50 ling member having its end tapped into the lower end of the secondary casing and provided with a flange designed to engage beneath the first-named flange, a valve-seat provided in the secondary casing, and a valve movably disposed within the latter and normally resting upon the seat.

In testimony that I claim the foregoing as my own I have hereto affixed my signature in the presence of two witnesses.

JULIAN DORIOT.
